Primary Examiner — Karen S Acker*Assistant Examiner* — Jasmine Mlinarcik(57) **CLAIM**

The ornamental design for a cap with hair scrunchies, as shown and described.

DESCRIPTION

FIG. 1 is a top, rear perspective view of the cap with hair scrunchies showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a cross-sectional view taken on line 8-8 of FIG. 6. The broken lines shown in the drawings illustrate portions of the cap with hair scrunchies that form no part of the claimed design.

The dash-dot-dot-dash broken lines in FIG. 8 showing the cap with hair scrunchies in use illustrates environment and forms no part of the claim.

1 Claim, 5 Drawing Sheets(56)
